BLIND STITCHING MEANS

Sylvester J. Birginal, Chicago, Ill.

Application April 24, 1946, Serial No. 664,661

10 Claims. (Cl. 112—140)

1

This invention relates to a blind stitching apparatus and more particularly to an attachment for a conventional sewing machine adapted to make it convertible into a blind hemmer or back to conventional use with the minimum of effort or trouble.

This invention is an improvement on the structure shown and claimed in my copending application for a blind stitching apparatus heretofore filed on July 8, 1944, as Serial No. 544,051.

One feature of the structure shown in this and in the aforesaid copending application is that it provides improved blind stitching apparatus. Another feature is that the apparatus embodying this invention may be used in blind sewing work of flat or small or large tubular design on a conventional sewing machine without the need of a tubular knee, a special bed, or the like. Still another feature is that it includes means for precisely adjusting the position of the means guiding the material being sewed, this adjustment being with respect to the path of the needle of the sewing machine and enabling proper blind stitching of materials of widely varying thicknesses. Yet another feature is that the adjusting means includes motion-reducing connections and calibrated indicating means facilitating setting of the apparatus for the material to be blind stitched.

The present invention has, in addition to the above features, the further feature that the guide plate or the guide member and associated pressure member for guiding the material being sewed may both be swung out of operating position and into a non-operating position wherein the guide member is flush with the throat plate of the machine. Yet another feature of the present invention is that it provides a snap-action locking of the guide member in either the operating or non-operating position. Another feature of this invention is that the manual actuating means for precisely adjusting the guide member is located on the throat plate on the opposite side of the needle with respect to the guide member. A further feature is that the blind stitching apparatus is contained within the periphery of a throat plate of conventional size and shape.

Figure 1 is a side elevational view of the head and a portion of the bottom of a sewing machine including blind stitching apparatus embodying my invention; Figure 2 is an enlarged detailed view of a portion of the apparatus shown in Figure 1; Figures 3, 4 and 5 are illustrative of material during and after blind stitching of a hem therein, Figure 3 being a sec-

2

tional view of the material immediately after the stitch has been made therein, Figure 4 being a similar sectional view of the material unfolded into the shape into which it is worn and Figure 5 being a fragmentary view of the surface of the material indicating the path of the stitching; Figure 6 is a plan view of the throat plate and a portion of a bed of a sewing machine together with blind stitching apparatus embodying my invention, as illustrated in Figure 1; Figure 7 is a sectional view along the line 7—7 of Figure 6, the inoperative position of the guide member alone being shown in dotted lines; Figure 8 is a view partly in section of the underside of the throat plate of Figure 6; Figure 9 is a view, partly in section, along line 9—9 of Figure 8; Figure 10 is a sectional view along line 10—10 of Figure 8; Figure 11 is a view partly in section along line 11—11 of Figure 12; Figure 12 is a front elevational view of the presser foot and guiding arm for blind stitching.

The value and need for blind stitching in sewing articles such as the bottoms of men's trousers and the hems of women's skirts is well known. I have invented a blind stitching apparatus embodied in a throat plate of conventional shape which can be attached to the ordinary sewing machine by merely removing a few screws therefrom and replacing the throat plate with which the machine was originally supplied, with the throat plate embodying my invention.

The arrangement is such that the guiding means for guiding the path of the material closely adjacent the path of the needle can be swung into operating position for blind stitching, and it is held in that position by action of a snap lock. When it is desired to use the machine for conventional sewing, the guiding member can be swung to a non-operating position wherein it is held flush with the throat plate and presents no projections to catch on or interfere with the passage of material being stitched; and the spring-urged presser shoe can be swung up out of the way, so that no parts need be removed from the machine. The presser foot which is used in conjunction with the guiding member has two positions, one for blind stitching and one for conventional sewing, and is equipped with a spring-urged guiding arm to press the material being stitched against the guiding member.

In the particular embodiment of my invention illustrated herein, a conventional sewing machine is partially illustrated. Referring more particularly to Figure 1, this comprises a metal bed 20 mounted upon a wooden base or table arrange-

ment 21 and a conventional head 22 having a reciprocable needle carrier 23 in which needle 24 is mounted for longitudinal reciprocable movement. A presser foot, which will be more fully described later, serves to hold down the material being sewed and a feed comprising horizontal reciprocable toothed members, of sufficient length to effect proper feeding of the material being sewed in either of the positions of the presser foot, serves to move the material in desired synchronization with the needle reciprocation. These toothed members will for the most part not be further described here, it being understood that my blind stitching attachment may be used on the conventional sewing machine so long as longer dogs are associated with it.

As may be best seen in Figures 6-10, the throat plate 25 is of conventional shape and is provided with a throat hole or opening 26 in which the needle is reciprocable. On the underside of the throat plate, as best seen in Figure 8, is the mounting plate or mounting member here identified as 27. The mounting member is slidable longitudinally (that is, in a direction perpendicular to the direction of movement of the needle) in slots 28, being guided in said slots by screw members 29 attached to the underside of the throat plate and projecting through and engaging the slots 28. Longitudinal movement of the mounting member is achieved through the lever 30, this lever being pivotally mounted to the throat plate at 31, and pivoted to lever member 32 at 33 as shown. Lever member 32 is pivoted to the throat plate at 34 and pivotally attached to the mounting member at 35 as shown. It can be seen that moving lever member 30 in a clockwise or counter-clockwise direction serves through the lever members just described to move the mounting member longitudinally in slots 28. Lever member 30 protrudes through slot 36 to the upper side of the throat plate and terminates in a pointer 37 above the indicating scale 38 on the right hand side of the throat plate, as viewed in Figure 6.

As seen in Figure 7, the mounting member 27 has at its left hand side a downwardly projecting portion 39 terminating in a shoulder 40. A cylindrical collar 41 is fixed on the shoulder 40 as shown, and is provided with a hole aligned with a hole of similar size in the shoulder 40 to receive the pivot 42. Pivot 42 is rotatably mounted in and projects through the holes just mentioned to a point some distance below the shoulder 40, terminating in a threaded end 43 on which nut 44 is screwed. A compression spring 45 is interposed between nut 44 and shoulder 40 to constantly exert a downward pressure on the pivot 42. Fixed to the upper end of pivot 42 is the guiding member 46 of the general shape as shown in Figure 6, and the guiding member is provided with a slot 47 adapted to be aligned with the needle 24 when the guiding member is in the operative position shown by the solid lines of Figure 6. The collar 41 has a diagonally cut away portion 48 to act as a cam, upon which cam the pin 49 (which is integral with the pivot 42) rides. The arrangement is such that when the guide member 46 is in the operating position shown by the solid lines in Figures 6 and 7, the pin 49 is in the position shown in Figure 9, that is, at the upper portion of cam 48, and is held in that position in a slightly downwardly inclined portion of the cam by the tension of the spring 45 (the downwardly inclined portion, the pin and the spring cooperate to form a snap action lock), and the guide member is spaced above the throat

plate, as shown, and positively held against rotation when the material passes along its guiding edge during sewing. Rotating the guide member approximately 180° in a clockwise direction, as viewed in Figure 6, will cause the pin 49 to ride down the diagonal cam portion 48 lowering the guide member until the pin is in the position shown at the left hand side of Figure 10. At that time the guide member will be in the non-operating position wherein it is in the same plane, that is flush with the throat plate 25 (this position being illustrated by the dotted lines in Figures 6 and 7), and held in that position by the tension of the spring. The portion of the guide member around the pivot 42, when swung to the non-operating position just described, fits into a cut-away portion 50 of the throat plate. While in the operating position, the material guiding edge 51 of the guide member can be precisely adjusted towards or away from the needle by the actuation of lever 30, the guide member being held against movement in a direction parallel to the path of movement of the needle by pivot 42.

In conjunction with my invention as herein disclosed, I prefer to use a special presser foot. As this presser foot is fully described in my copending application heretofore referred to, it will be but briefly described herein, as comprising an ordinary presser foot 53 (Figures 11 and 12) and a vertical shank portion 54 mountable on the presser foot supporting member 55 in two spaced positions.

A mounting bracket 56 is rotatably mounted on shaft 57, and a guiding arm 58 is pivotally mounted on the mounting bracket as shown.

Torsion spring 59 urges the guiding arm and the pressure shoe 60 against the edge of the material being sewed, the torsion spring providing great flexibility, thus freely permitting smooth passage of seams, and shaft 57 provides means of swinging the guiding arm approximately 90° about the axis thereby provided to a compact, out of the way, non-operating position when it is desired to do conventional sewing.

The way in which my attachment facilitates blind stitching, and more particularly blind hemming, will be best understood from a consideration of Figures 2-5 inclusive. In loading the machine for blind stitching, the material is folded into a double fold as shown in Figures 2 and 3 and, with the guide member in inoperative position, the folded material is placed under the lifted presser foot so that the portion 63 is directly under the needle, and the presser foot is then dropped down to exert pressure on the material and hold it in place. With the material lying thus and held by the presser foot, the horizontal pivotal action of the guide member provides a very convenient and easy method of inserting the guide means into the fold between layers 62 and 64, so that its material guiding edge 51 is against the portion 63 of the fold, merely by a swinging movement of the member 46. Referring first to Figure 2, it will be seen that the material to be hemmed, as the bottom of a trouser leg, here identified as 61, has a portion 62 overlying the guide member 46 and a portion 63 bent around the guiding edge 51 of the guide member, a portion 64 extending back to the left under the guide member, another curved or folded portion 65 which is to become the bottom of the garment, and a straight portion 66 extending back under the portion 64 and slightly out beyond the needle, these portions 64 and 66 lying on each other between the throat plate 25 and the guiding mem-

ber 46. The material is so placed during this operation that the wrong side of the material faces upwardly in the part 62, downwardly in the part 64, and upwardly again in the part 66. The guiding edge 51 of the guide member is preferably spaced from the center of the path of movement of the needle 24 by a distance equal to about one-half the thickness of the material so that during the sewing operation the needle pierces the middle of the folded end portion 63 in the manner shown and then passes straight through the right hand end of the portion 66 of the material. The fold 63 of the material is held in proper relation to the guiding edge 51 of the guide member 46 by the arcuate surface of the pressure shoe 60.

As the material is moved beyond the stitching point it appears substantially as illustrated in Figure 3, the parts of the material being stitched together by the thread 67. When the hem has been finished and the fold or bend 63 is straightened out, the material appears as shown in Figure 4 in cross-section and Figure 5 in elevation, the stitching being shown in dotted lines because it is not visible through the right side of the material.

While I have shown and described certain embodiments of my invention, it is to be understood that it is capable of many modifications. Changes, therefore, in the construction and arrangement may be made without departing from the spirit and scope of the invention as disclosed in the appended claims.

I claim:

1. In a sewing machine having a reciprocal needle, apparatus of the character described rendering the machine readily convertible for blind stitching or conventional stitching, including: a throat plate for replacing the throat plate of the machine; a guide member insertable into a fold of the cloth to guide said fold while it is being stitched, and adapted to have the material guiding edge closely adjacent the path of movement of the needle; a mounting member having the guide member pivotally mounted thereon, the mounting member being movable in a plane perpendicular to the direction of movement of the needle; and actuating means for moving the mounting member to adjust the position of the guiding edge of the guide member with respect to the path of movement of the needle, the actuating means including a manually movable actuating member and a motion reducing actuating connection between said actuating member and the mounting member, said guide member, said mounting member and at least the major portion of said actuating means being contained within the periphery of the throat plate.

2. In a sewing machine having a reciprocal needle, blind stitching apparatus of the character described, including a throat plate of conventional size and shape: a guide member insertable into a fold of the cloth to guide said fold while it is being stitched and adapted to have a material guiding edge closely adjacent the path of movement of the needle; a mounting member mounted on said plate and having the guide member pivotally mounted thereon, the mounting member being movable in a plane perpendicular to the direction of movement of the needle; and actuating means for moving the mounting member to adjust precisely the position of the guiding edge of the guide member with respect to the path of movement of the needle, the actuating means including a manually movable actuating

member positioned on the opposite side of the needle from the said guide member and mounting member, and a motion reducing actuating connection between said actuating member and the mounting member.

3. Apparatus of the character described, rendering a sewing machine readily convertible for blind stitching or conventional stitching, including: a throat plate of conventional size and shape having a hole adapted to receive the end of the reciprocal needle of a sewing machine; a guide member having an operating and a non-operating position; a mounting member attached to said throat plate and being movable in a plane perpendicular to the direction of movement of the needle and having the guide member pivotally mounted thereon said pivot extending through a cut-away portion in the throat plate, the mounting being such that said guide member is adapted while in the operating position to be spaced above the throat plate and to have a material guiding edge closely adjacent the path of the needle and is adapted while in a non-operating position to be received in said cut-away portion wherein it is flush with the throat plate.

4. Apparatus of the character described, rendering a sewing machine readily convertible for blind stitching or conventional stitching, including: a throat plate having a hole adapted to receive the end of the reciprocal needle of a sewing machine; a guide member having an operating and non-operating position; a mounting member attached to the under side of the throat plate and being movable in a plane perpendicular to the direction of movement of the needle and having the guide member pivotally mounted thereon about an axis parallel to the direction of movement of the needle said pivot extending through a cut-away portion in the throat plate, the mounting being such that said guide member is adapted while in the operating position to be spaced above the throat plate and to have a material guiding edge closely adjacent the path of the needle and is adapted to be pivoted about its axis approximately 180° to the non-operating position wherein it is received in said cut-away portion and is flush with the throat plate.

5. Apparatus of the character described, rendering a sewing machine readily convertible for blind stitching or conventional stitching, including: a throat plate of conventional size and shape having a hole adapted to receive the end of the reciprocal needle of a sewing machine; a guide member having an operating and a non-operating position and adapted to have a material guiding edge closely adjacent the path of movement of the needle; a mounting member attached to the under side of the throat plate and movable in a plane perpendicular to the direction of movement of the needle and having the guide member pivotally mounted thereon about an axis parallel to the direction of movement of the needle, said pivot extending through a cut away portion of the throat plate the mounting being such that said guide member is adapted while in the operating position to be spaced above the throat plate and to have the material guiding edge closely adjacent the path of movement of the needle and is adapted to be pivoted about its axis approximately 180° to the non-operating position wherein it is received in said cut-away portion; actuating means for moving the mounting member to adjust precisely the position of the guiding edge of the guide member with respect to the path of movement of the needle; and means for main-

staining the guide member in the operating and non-operating positions; said last named means including cam and spring means.

6. Apparatus of the character described for use in a sewing machine having a reciprocal needle and a presser foot supporting member for rendering the machine readily convertible for blind stitching or conventional stitching, including: a throat plate having slots therein for feed means and a hole adapted to receive the end of the needle; a guide member adapted to have a material guiding edge closely adjacent the path of movement of the needle; a mounting member having the guide member pivotally mounted thereon about an axis parallel to and spaced from the line of movement of the needle, said guide member being adapted to be pivoted about its axis to a position spaced above the throat plate and to have a material guiding edge closely adjacent the path of the needle and adapted to be pivoted about its axis approximately 180° from the first named position to a position wherein it is flush with the throat plate, the said mounting member being movable in a plane perpendicular to the direction of movement of the needle; actuating means for moving the mounting member to adjust precisely the position of the guiding edge of the guide member with respect to the path of movement of the needle, the actuating means including a manually movable actuating member, and a motion reducing actuating connection between said actuating member and the mounting member; a presser foot having means for connection to said supporting member in two spaced positions longitudinally of the line of stitch; a guiding arm pivotally mounted on said presser foot and having an end adapted to lie in front of one end of the presser foot; spring means for urging said end of the guiding arm toward said material guiding edge to press the material being sewed thereagainst; and feed means operable in the slots in said throat plate and of sufficient length to effect proper feeding of the material sewed in either position of the presser foot.

7. Apparatus of the character described for use in a sewing machine having a reciprocal needle and a presser foot supporting member for rendering the machine readily convertible for blind stitching or conventional stitching, including: a throat plate having a hole adapted to receive the end of the reciprocal needle of a sewing machine; a guide member having an operating and a non-operating position; a mounting member movable in a plane perpendicular to the direction of movement of the needle and having the guide member pivotally mounted thereon about an axis parallel to the direction of movement of the needle and movable about the pivot in a plane generally perpendicular thereto, said pivot being provided with means for spacing the guide member above the throat plate while in the operating position wherein the guide means is adapted to have a material guiding edge closely adjacent the path of the needle and said means being adapted to maintain the guide member in a position flush with the throat plate while said guide member is in the non-operating position; a presser foot having means for connection to said supporting member in two spaced positions longitudinally of the line of stitch; a guiding arm pivotally mounted on said presser foot and having an end adapted to lie in front of one end of the presser foot; spring means for urging said end of the guiding arm toward said material

guiding edge to press the material being sewed thereagainst.

8. Apparatus of the character described for use in a sewing machine having a reciprocal needle and a presser foot supporting member for rendering the machine readily convertible for blind stitching or conventional stitching, including: a throat plate of conventional size and shape having a hole adapted to receive the end of the reciprocal needle of a sewing machine; a guide member having an operating and a non-operating position; a mounting member attached to said throat plate and being movable in a plane perpendicular to the direction of movement of the needle and having the guide member pivotally mounted thereon, said pivot extending through a cut-away portion in the throat plate, the mounting being such that said guide member is adapted while in the operating position to be spaced above the throat plate and to have a material guiding edge closely adjacent the path of the needle and is adapted while in a non-operating position to be received in said cut-away portion wherein it is flush with the throat plate; a presser foot having means for connection to said supporting member in two spaced positions longitudinally of the line of stitch; a guiding arm pivotally mounted on said presser foot and having an end adapted to lie in front of one end of the presser foot; spring means for urging said end of the guiding arm toward said material guiding edge to press the material being sewed thereagainst.

9. Apparatus of the character described for use in a sewing machine having a reciprocal needle and a presser foot supporting member for rendering the machine readily convertible for blind stitching or conventional stitching, including: a throat plate of conventional size and shape having a hole adapted to receive the end of the reciprocal needle of a sewing machine; a guide member having an operating and non-operating position; a mounting member attached to the underside of the throat plate and being movable in a plane perpendicular to the direction of movement of the needle and having the guide member pivotally mounted thereon about an axis parallel to the direction of movement of the needle, said pivot extending through a cut-away portion of the throat plate, the mounting being such that said guide member is adapted while in the operating position to be spaced above the throat plate and to have a material guiding edge closely adjacent the path of the needle and is adapted to be pivoted about its axis approximately 180° to the non-operating position wherein it is received in said cut-away portion and is flush with the throat plate; a presser foot having means for connection to said supporting member in two spaced positions longitudinally of the line of stitch; a guiding arm pivotally mounted on said presser foot and having an end adapted to lie in front of one end of the presser foot; spring means for urging said end of the guiding arm toward said material guiding edge to press the material being sewed thereagainst.

10. Apparatus of the character described for use in a sewing machine having a reciprocal needle and a presser foot supporting member for rendering the machine readily convertible for blind stitching or conventional stitching, including: a throat plate of conventional size and shape having a hole adapted to receive the end of the reciprocal needle of a sewing machine; a mounting member mounted on the underside of said throat plate and movable in a plane perpendicular to the direction

of movement of the needle; a guide member having an operating position wherein it is adapted to have a material guiding edge closely adjacent the path of movement of the needle, and having a non-operating position; a pivot having one end attached to the guide member and extending through a cut-away portion in the throat plate and through an opening in a portion of the guide member; a compression spring interposed between the other end of said pivot and the edges of said opening for constantly exerting the downward tension on said pivot; a cylindrical collar attached to said portion having a cam surface; a pin integrally attached to said pivot and adapted to ride on said cam surface, said cam and pivot being so constructed and arranged so as to maintain the guide member in a position spaced above the throat plate while in the operating position, and said guide member being adapted to be rotated approximately 180° from the operating position to the non-operating position, said rotation causing said pin to travel on a downwardly extending surface of said cam whereby said guide member is lowered into said cut-away portion wherein it is flush with the throat plate, a presser foot having means for connection to said supporting member

in two spaced positions longitudinally of the line of stitch; a guiding arm pivotally mounted on said presser foot and having an end adapted to lie in front of one end of the presser foot; spring means for urging said end of the guiding arm toward said material guiding edge to press the material being sewed thereagainst.
